Inventor:

John D. Mohr,
by *John D. Mohr, Atty's.*

UNITED STATES PATENT OFFICE.

JOHN D. MOHR, OF OIL CITY, PENNSYLVANIA.

POSTAGE-STAMP RECEPTABLE AND APPLYING DEVICE.

1,244,532.

Specification of Letters Patent. Patented Oct. 30, 1917.

Application filed October 12, 1916. Serial No. 125,259.

To all whom it may concern:

Be it known that I, JOHN D. MOHR, a citizen of the United States, residing at Oil City, Pennsylvania, have invented certain new and useful Improvements in Postage-Stamp Receptacles and Applying Devices, of which the following is a specification.

My invention is designed primarily to carry stamps and to provide for their application to the letters or other mail matter through the medium of the receptacle and its associated parts so as to render unnecessary the licking of the stamp and its application in the ordinary way, but the invention by slight changes can be adapted for use in the application of labels and stickers of all kinds including the moistening and sealing of envelopes.

I am aware that it has been proposed prior to my invention to provide devices of this general type, but my invention is unique in its structure and is not only simple but very effective.

In the accompanying drawing,

25 Figure 1 is a section showing the moistening means, the stamp compartment and the applying device.

Fig. 2 is a section showing the plunger in a depressed position for the applying of 30 the stamp or other article.

Fig. 3 shows the device tilted with the roller in action.

Fig. 4 is a bottom plan view, and

Fig. 5 is a detail of the plunger.

35 A case *a* is provided with two compartments *b* and *c*, *b* containing the moistening medium which is entered through the cap *d*, and a wicking or felting *e* protrudes through a passage *f*, and enables the user of 40 the device to moisten the surface to which the stamp is to be applied. Directly beneath the compartment *b* is located a roller *g*, which applies pressure to the stamp or other article after it has been placed upon 45 the letter or other surface subsequent to the

moistening of the surface as shown in Fig. 3. A plunger plate *h* is supported upon the stem *k*, which in turn is supported by the spring *i*. A knob *l* serves to depress the stem. The plunger is of the shape shown in Fig. 5 and has a rib *m* depending from its lower face to one side of the center. The receptacle has a spring supported bottom section *n*, the spring being shown at *o*, and normally presses the plate upwardly. The stamps are inserted within the receptacle occupying the position normally as shown in Fig. 1, being pressed upwardly by the section *n*. This plate does not entirely cover the bottom of the casing and hence as the plunger is forced down, as shown in Fig. 2, it will be noted that the edge of the lowermost stamp or other article is forced into contact with the previously moistened surface of the envelop or other surface and then it is only necessary to tilt and roll the receptacle as shown in Fig. 3 to cause the stamp to pass from the receptacle and come under the pressure of the roller to apply it securely.

70 The stamps may be inserted through the bottom of the receptacle, or the top may be hinged so as to permit the withdrawal of the plunger and thus permit of the insertion of the stamps through the top of the receptacle.

Having thus described my invention what I claim is:

An affixing device including moistening means, a stamp container having a spring bottom and a plunger having a downwardly extending rib in line with the opening in the bottom adapted when the plunger is depressed to bring the bottom stamp in contact with the moistened surface intermediate between the edge of the spring plate and the free edge of the stamp, substantially as described.

80 85 In testimony whereof, I affix my signature.
JOHN D. MOHR.
